2 SHEETS—SHEET 2.

UNITED STATES PATENT OFFICE.

DOLLIVER M. DEAN, OF LACON, ILLINOIS, ASSIGNOR, BY MESNE ASSIGNMENTS, TO
MARY W. DEAN, OF PEORIA, ILLINOIS.

CONCRETE BLOCK FOR CULVERTS.

1,404,935.

Specification of Letters Patent. Patented Jan. 31, 1922.

Application filed February 10, 1919. Serial No. 275,970.

To all whom it may concern:

Be it known that I, DOLLIVER M. DEAN, a citizen of the United States, a resident of Lacon, in the county of Marshall and State 5 of Illinois, have invented new useful Improvements in Concrete Blocks for Culverts, of which the following is a specification.

This invention has reference to concrete blocks, preferably hollow in construction, 10 and designed more particularly for culvert uses.

The invention has for its object to improve reinforced hollow concrete block sections and to provide a new and novel connecting 15 means for uniting the adjoining block sections.

That the invention may be more fully understood, reference is had to the accompanying drawings, forming a part of the description, in which:—

Fig. 1 is a side elevation of a hollow block embodying my invention;

Fig. 2 is an end elevation of Fig. 1;

Fig. 3 is a cross-section as the same would appear, if taken on the line 3—3 of Fig. 1;

Fig. 4 is a cross-section as the same would appear, if taken on the line 4—4 of Fig. 1;

Fig. 5 is a detail sectional view, in elevation, showing the connecting means for 30 uniting adjoining blocks, and

Fig. 6 is a detail cross-section, in plan, of the connecting means, seen in Fig. 5.

Like characters of reference denote corresponding parts throughout the figures.

The block 1 in length and cross-section is not unlike blocks of this character now being manufactured, having the side walls 2, the top and bottom walls 3 and end walls 4.

Each block is reinforced as follows: 5 designate longitudinally arranged rods or bars, preferably located at the corners, and 6 are rods or bars placed midway between the bars or rods 5 and embedded in the side 45 walls 2. 7 designate a plurality of spaced rods or bars which are arranged transversely through the top wall 3 and bent down and over the upper opposite corner rods or bars 5 and embedded in the side walls 2 to a point approximately coinciding with the rods or bars 6.

Similar rods or bars 8 are located at or near the opposite ends of the block but are embedded, as shown, in the top and bottom 55 walls 3, the side walls 2 and are bent at the

corners over the rods or bars 5. Extending longitudinally of the block embedded in the top and bottom walls 3 are a plurality of spaced rods or bars 9. In the upper wall 3 these rods or bars 9, preferably overlie 60 the rods or bars 7 and 8, and in the lower wall 3 said rods or bars preferably underlie the rods or bars 8.

The vertical sides of the end walls 4, as shown in Fig. 2, are provided with, preferably, semi-circular grooves 10 extending from the top of the block to a point removed a short distance from the bottom of the block, and said grooves are intersected, where the rods or bars 5 and 6 pass therethrough, by preferably, semi-spherical sockets 11.

During the formation of the block 1, the rods or bars 5 and 6 are preferably laid in the material, inclined from one end to the other with their ends bent into a loop 12, V shaped, see Fig. 6, and with the ends of the loops made fast in the material, and the arcuate ends of the looped ends projecting slightly beyond the end of the block. 70

Inclining the rods or bars 5 and 6 presents their looped ends 12 so that adjacent blocks may be caused to abut, see Fig. 5, with the loops 12 on the rods or bars 5 and 6 in one block, overlying, or underlying, as 85 may be the case, the loops 12 on the rods or bars 5 and 6 in the other block, and when so positioned a rod or bar 13 is passed down through the matching loops 12 to unite them, said rod or bar 13 being located in 90 the matching grooves 10 in the blocks, and when the parts have been so connected the grooves 10, as well as the matching semi-spherical sockets 11 are filled with a binder 14 such as asphaltum, or other suitable or 95 desirable filler.

The blocks thus constructed and connected are insured against moisture getting to the rods or bars, and such connections, therefore, will last as long as the blocks themselves. 100

What I claim is:—

1. In combination, a hollow concrete block provided with reinforcing rods embedded therein, in spaced relation and extending longitudinally thereof at the corners and through the top, bottom and sides, reinforcing rods embedded in the block at the opposite ends thereof and overlying and underlying certain of said first mentioned 110

rods, and a plurality of reinforcing rods embedded in the block in spaced relation between said second mentioned rods and extending through the top and partially 5 down the opposite sides and overlying and underlying certain of said first mentioned rods.

2. In combination, a rectangular hollow block provided at its ends and on opposite 10 sides of the opening therethrough with vertically disposed semi-spherical grooves opening out of the top of the block and closed at the bottom and at intervals inter-

sected by semi-spherical sockets, reinforcing rods embedded in said block and extending 15 longitudinally thereof at the corners and intermediate the corners and intersecting said semi-spherical sockets in the ends, loops formed on the ends of said rods, and other rods embedded in the tops and sides of 20 said block and spaced at intervals throughout the length of said block.

In witness whereof, I have hereunto affixed my hand this 21st day of January, 1919.

DOLLIVER M. DEAN.
